COMBINATION FINGERNAIL FILE, FINGER-NAIL CLIPPER, AND POCKET CLIP

Richard J. Franklin, Bismarck, N. Dak.

Application July 5, 1951, Serial No. 235,191

1 Claim. (Cl. 30—28)

1

This invention relates to a combined fingernail file, nail clipper and combination clipper lever and pocket clip.

The primary object of the invention is to provide a fingernail file having a resiliently operable clipper extension and a lever means for operating the clipper, the lever means being of such construction that when moved into a particular position will serve as a pocket clip. Not only will the file and clipper be capable of ready suspension in a pocket, but because of this the device will include a relatively long and useful file rather than the short useless files found on conventional files and clippers presently on the market. The present device is also inexpensive and easy to operate.

These, together with various ancillary objects and features of the invention which will later become apparent as the following description proceeds, are attained by the device, a preferred embodiment of which has been illustrated, by way of example only, in the accompanying drawings, wherein:

Figure 1 is a perspective view of the device;

Figure 2 is a side elevation;

Figure 3 is a top plan view with the combined lever and pocket clip removed;

Figure 4 is a top plan view of the entire device;

Figure 5 is a sectional view taken on the line 5—5 of Figure 1; and

Figure 6 is a side view of the device shown suspended on a pocket, the latter being shown in section.

Specific reference will now be made to the drawings. In the several views, in the accompanying drawings and in the following specification, similar reference characters indicate corresponding elements throughout.

The present device comprises an elongated nail file 10 having a pointed end 12 and an opposite resilient bifurcated end 14 having normally spread apart members or furcations 16 and 18 terminating in finger-nail clipping jaws or cutters 20. Extending slidably through the furcations is a rivet or pin 22 having a head 24 at its bottom end and a hook-shaped cam slot 26 adjacent its free end.

A combined lever and pocket clip is provided in the form of an elongated tapered bar 28 having a knob 30 at one end thereof, the opposite end being a forked extension 32 at an angle to the axis of said bar, the forked extension having furcations or legs 34 and 36 straddling said pin 22 and carrying a pin 38 engaged in the hook-shaped slot 26 of the headed pin 22. The legs have cams 40 which bear on the furcation 18 of the clipper so that when the lever bar 28 is urged towards the file 10, the jaws 20 of the clipper will close. On both sides of the pin 22, the furcation 18 is provided with longitudinal grooves 42 while the 60

2

free ends of the legs 34 and 36 of the fork 32 are provided with upstanding lips or flanges 44.

In use, a movement of lever 28 towards the file will close the jaws 20. If the lever is moved through a 180° angle and then moved toward the file, the flanges 44 will engage in the grooves 42 and hold the lever as a pocket clip capable of engaging the flap 46 of a pocket 48. Thus, the lever functions as a means for operating the clipper and as a means for suspending the device on and in a pocket.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claim.

Having described the invention, what is claimed as new is:

A manicure instrument of the character described comprising a pair of elongated, resilient, divergent jaw members secured together at one end, coacting blades on the free ends of said members, a headed, notched rivet swivelly mounted on one of the members and extending rotatably through the other of said members, said other member having longitudinal grooves therein adjacent the rivet, and a reversible operating lever for closing the members, said lever including furcations on one end straddling the rivet, a pin extending between the furcations at an intermediate point and engaged in the notch of the rivet for operatively connecting said lever thereto, longitudinal cams on one side of the furcations inwardly of the pin and engageable with said other member for closing the members when the lever is in operating position, and lips on the other side of the furcations outwardly of the pin, operable in the grooves and engageable with said other member for securing the lever in reversed position.

50 RICHARD J. FRANKLIN.
